UNITED STATES PATENT OFFICE.

JOHN M. SHIMER, OF WILKINSBURG, PENNSYLVANIA, ASSIGNOR TO WILSON-SNYDER
MANUFACTURING COMPANY, A CORPORATION OF PENNSYLVANIA.

PUMP.

Application filed April 20, 1927. Serial No. 185,156.

This invention relates to pumps and more particularly to displacement pumps of the piston or plunger type.

An object of this invention is to provide a pumping mechanism of such construction and arrangement as to permit either simplex or duplex operation.

A further object is to provide a control mechanism for separate pump units constructed and arranged to permit the separate units to be operated as independent simplex units or to be combined so as to provide a duplex pump.

A still further object is to provide a pumping mechanism of such arrangement as to be capable of operation as a single system or as a plurality of separate systems.

A still further object is to provide a pumping mechanism of the type set forth which will be rugged in construction, simple in arrangement and easy to operate.

These and other objects which will be apparent to those skilled in this particular art are accomplished by means of the invention illustrated in the accompanying drawings in which Figure 1 is a diagrammatic view of a piping layout forming a control system constructed in accordance with one embodiment of this invention. Fig. 2 is a view in elevation of a control panel for use with the piping arrangement shown in Fig. 1. Fig. 3 is a diagrammatic view of the supply and discharge connections associated with the pump units employed in connection with the invention illustrated in Fig. 1 and Fig. 4 is a sectional view showing the relative arrangement of the steam pilot valve employed in connection with each of the pump units.

The particular embodiment of this invention which has been chosen for the purposes of illustration contemplates the use of two separate and distinct pump units. Piping connections are associated with the pilot valve and with the steam valve of each unit in such a way that the two units can be operated separately as simplex pumps or they may be combined together to provide a single duplex pumping unit, and this is true even when the main steam valves of the two units are operated by steam under the control of pilot valves instead of being operated mechanically. Suitable valves control the piping and a single operating lever is employed for simultaneously shifting the

various valves so that either simplex or duplex action may be obtained by the throwing of the single lever. The supply and discharge connections to each of the units are such that it is possible to operate each single unit as a simplex pump entirely independent of the other when this is necessary or desirable.

It is, of course, readily understood that, in order to operate a duplex pump, the steam valve of one cylinder must be operated by the movement of the piston rod in the other cylinder, and vice versa. This is normally accomplished by means of a set of levers and cranks which are operated by cross heads attached to the respective piston rods, as is well understood in this art. It is essential that these levers and cranks be so arranged that the steam valve in one cylinder moves in the same direction as the piston rod of the other cylinder which operates it, while the steam valve of the latter cylinder must be moved in the opposite direction from the piston rod of the first cylinder which operates it.

In order to operate a simplex pump, the steam valve of the single cylinder must be moved each time in a direction opposite to the direction of the piston travel. These various relative movements of steam valves and operating piston rods are well understood by those skilled in this art, and, it will be apparent from the following description, that the present invention takes care of these various conditions of operation for both duplex and simplex arrangements.

As illustrated, the present invention includes a standard simplex pump unit 5 and a second similar unit 6, each of which is provided with the usual steam chest 7 having the slidable steam valve 8 of standard construction. The steam valves 8 are adapted to be operated by steam pressure from the chest 7, the flow of which to different sides of the valve 8 is controlled in the first unit 5 by a pilot valve 9 of standard construction having a rotatable valve member 10 which is oscillated in the usual manner to control the flow of operating steam to the associated steam valve 8. The pilot valve 9 has the usual exhaust connection 12. The valve ports instead of being connected to the respective sides of the steam valve on the same unit are connected to a piping arrangement which forms a control system for

effectively controlling the various pumping operations. One valve port of the pilot valve 9 on the first unit is connected to piping 13, see Fig. 1, leading to a control panel 14 where it is connected to a three-way valve 15, which in turn is connected on one side to piping 16 leading back to one side of the steam valve in that unit, while the other side of the three-way valve is connected to piping 17 leading to one side of the steam valve on the other pump unit 6. The other port of the pilot valve 9 on the pump unit 5 is connected to piping 18 leading to a second three-way valve 19 also mounted on the control board and connected at one side to piping 20, leading back to that side of the steam valve in the unit 5 opposite to the side connected to the piping 16. A third port of the valve 19 is connected to piping 21 which communicates with the opposite side of the steam valve of the unit 6 from that of the piping 17. The second pump unit 6 has a pilot valve 22 similar in all respects to the pilot valve of the other unit. It is adapted to control the flow of steam to the steam valve of the other unit 5 when the two units are operated as a duplex pump or it is adapted to control the flow of operating steam to the steam valve upon its own unit 6 when the latter is operated as a simplex pump independent of the other unit 5. For this purpose one port of the pilot valve 22 is connected to piping 23 leading to a three-way valve 24 on the control board 14 and one side of which is connected by a connection 25 to a T 26, communicating at one side with the piping 17 and through it to the steam valve of the unit 6. The third port of the three-way valve 24, to which the piping 23 leads, is connected by piping 27 to the piping connection 20 leading to the one side of the steam valve in the unit 5. The other port of the pilot valve 22 on the unit 6 is connected by piping 29 to a fourth three-way valve 30 also mounted on the control panel 14 and connected by a short piping 31 to the piping 16. The other port of the three-way valve is connected by a connection 32 to the piping 21.

Each of the four three-way controlling valves mounted on the control panel 14 is adapted to be operated by a single valve operating lever 33 supported upon a pivot pin 34 and having pin and slot connections 35 with two valve operating yokes 36. The piping arrangements above described together with the three-way control valves are so arranged that when the valve operating lever is moved to the left, as shown in Fig. 2, the pilot valve 9 on the first pump unit 5 is connected to opposite sides of the steam valve in the second unit 6 so as to control its operation, while the pilot valve 22 on the second unit 6 is connected to the steam valve on the first unit 5 so as to control the lat-

ter's operation, thus uniting the two units and causing them to operate as a single duplex pump. When the valve operating lever is moved to the right, as shown in Fig. 2, the pilot valve on each unit is connected to the opposite sides of the steam valve on the same unit, thus providing two separate simplex pumps.

The supply and discharge connections of the two units are so arranged that the latter can be operated as parts of entirely separate systems or the supply and discharge connections can be associated so as to form a single system. As illustrated in Fig. 3, the supply line 37 for the pump unit 5 is connected through a valve 38 with a supply line 39, and it is also connected through a valve 40 with a separate supply line 41 so that by opening or closing one or the other of the valves 38 and 40 pump unit 5 will be supplied from one or the other of the separate supply lines 39 or 41. Similarly, the pump unit 6 has a supply pipe 42 connected through a valve 43 with the first supply line 39 and also connected through a valve 44 with the second supply line 41. It will be apparent that if valves 38 and 43 are both open while valves 40 and 44 are closed, the pump units 5 and 6 will be supplied from a single source; while if the valve 38 is closed and the valve 40 opened the first pump unit 5 will be connected with the supply line 41 and the second pump unit 6 connected with the first supply line 39. The discharge pipe 45 of the first unit 5 is connected through a valve 46 with a discharge line 47 and through a second valve 48 with a second discharge line 49. Similarly, the discharge pipe 50 of the second pump unit 6 is connected through a valve 51 with the first discharge line 47, and through a second valve 52 with the second discharge line 49. Either pump unit can operate in connection with either supply and either discharge line.

Assuming that it is desirable to operate the two pump units as separate simplex units, the operating lever on the control panel 14 will be moved to the right, as shown in Fig. 2. This will position the three-way control valves so that the steam flow through the control system will be as indicated by the solid arrows in Fig. 1. It will be seen that steam will flow through the port in the pilot valve 9 which is connected to the piping 18 to the three-way valve 19, thence through the piping 20 to one side of the steam valve on the same unit 5. The other port of the pilot valve 9 is connected by piping 13 with the three-way valve 15 and valve operating steam will flow through piping 13, valve 15 and through piping 16 to the other side of the same steam valve. Obviously, the operation of the pump unit 5 will be that of an independent simplex unit. In like manner

one port of the pilot valve 22 on the second pump unit 6 is connected through the piping 23, three-way valve 24, connection 25 and piping 17 with one side of the steam valve in the unit 6, while the other port of the pilot valve 22 is connected through piping 29 with the three-way valve 30, connection 32 and piping 21 to the other side of the steam valve of the second unit 6. Obviously, this unit 10 6 will then operate as a separate independent simplex unit.

When it is desired to operate the two pump units 5 and 6 as a single duplex pump in which the pistons are provided with the 15 overlapping stroke essential to true duplex operation the valve controlling lever 33 is moved to the left, as shown in Fig. 2. When in this position the steam flow is as shown by dotted arrows on Fig. 1. The pilot valve 20 on the unit 5 is then connected with the steam valve of the unit 6 and vice versa so that the steam valves on each side of the duplex pump will be operated by the pistons on the other sides. Operating steam for 25 the steam valve in the unit 6 will flow from the pilot valve 9 through the piping 18, three-way valve 19, piping 21 to the steam valve of the unit 6. From the other port of the pilot valve 9 steam will flow through 30 piping 13, three-way valve 15 and piping 17 to the opposite side of the steam valve in the unit 6. Similarly the pilot valve 22 of the pump unit 6 controls the operation of the steam valve in the pump unit 5. One port 35 of the pilot valve 22 is connected through piping 23 and three-way valve 24 to the connection 27, leading to the piping 20, connecting with one side of the steam valve of unit 5. The other port of the pilot valve 22 is 40 connected through piping 29, three-way valve 30 and connection 31 to piping 16, leading to the other side of the steam valve in the unit 5. When the two units are associated together into a single duplex pump, 45 they are connected to the same supply and discharge systems. For example, the valves 40 and 44 may be closed and the valves 38 and 43 opened so that the supply pipes of both units are fed from the supply line 39. 50 Obviously, the line 39 can be cut off and the second supply line 41 used to supply both units if desired. Similarly, each unit is connected to a single discharge line for duplex operation. The supply and discharge arrangements for simplex operation may be 55 as desired. If it is necessary to shut down any of the units, for example, during duplex operation, the valves associated with the supply and discharge lines of that unit may 60 all be closed and the other unit employed for continuing the circulation through the system. This is particularly advantageous in the pumping of hot liquids, such, for example, as hot oil employed in cracking plants. 65 As heretofore pointed out each pilot valve is

operated in the usual manner as is well known in the art.

Although I have described what I now consider to be the preferred arrangement of this invention it will be apparent that various changes, additions, omissions and substitutions can be made therein without departing from the spirit of the invention or the scope of the appended claims.

What I claim as new and desire to secure 75 by Letters Patent is:

1. The combination with independent steam cylinders and pistons, each having pilot and steam valves, of a control system 80 including piping connections between each pilot valve and each steam valve, and mechanism for controlling the flow through said connections so that the pilot valve on each cylinder is connected to the steam valve on the same cylinder for independent operation of said pistons, or the pilot valve on each cylinder is connected to the steam valve of the other cylinder for duplex operation of said pistons.

2. The combination with independent 90 steam cylinders and pistons, each having pilot and steam valves, of a control system including piping connections between each pilot valve and each steam valve, a central control station, and means at said station 95 for controlling the flow through said piping connections so that the pilot valve on each cylinder is connected to the steam valve of the same cylinder for independent operation of said pistons, or is connected to the steam valve on the other cylinder for duplex 100 operation of said pistons.

3. The combination with independent steam cylinders and pistons, each having pilot and steam valves, of a control station, 105 piping connections between said control station and each of said pilot and steam valves, control valves for directing the flow through said piping connections so as to cause said pistons to operate independently of each other or to cause said pistons to operate as a 110 duplex unit.

4. The combination with independent steam cylinders and pistons, each having pilot and steam valves, of a control station, 115 piping connections between said control station and each of said pilot and steam valves, control valves for directing the flow through said piping connections so as to cause said pistons to operate independently of each other or to cause said pistons to operate as a duplex unit, and a single lever for simultaneously operating said control valves.

5. The combination with independent steam cylinders and pistons, each having pilot and steam valves, of steam connections 120 between each pilot valve and each steam valve, and means for controlling the flow of steam through said connections so as to cause 125 said pistons to operate independently of each other.

other or to operate as a single duplex unit. 6. The combination with independent steam cylinders and pistons, each having pilot and steam valves, of mechanism for controlling the operation of each steam valve by the associated pilot valve or for controlling the operation of each steam valve by the pilot valve on the other cylinder, and a single operating lever for controlling said mechanism.

7. The combination with independent steam cylinders and pistons, each having

pilot and steam valves, of a fluid pressure mechanism for controlling the operation of each steam valve by the associated pilot valve or for controlling the operation of each steam valve by the pilot valve on the other cylinder, and a single operating lever for controlling said mechanism.

In testimony whereof, I have hereunto subscribed my name this 18th day of April, 1927.

JOHN M. SHIMER.
